(57) **CLAIM**

The ornamental design for a headset for telephone, as shown and described.

DESCRIPTION

FIG. 1 is a Top Front Right Side Perspective view of a headset for telephone showing the new design;

FIG. 2 is a Front Elevational view thereof;

FIG. 3 is a Rear Elevational view thereof;

FIG. 4 is a Left Side Elevational view thereof;

FIG. 5 is a Right Side Elevational view thereof;

FIG. 6 is a Top view thereof;

FIG. 7 is a Bottom view thereof;

FIG. 8 is a Top Front Right Side Perspective view of a second embodiment of a headset for telephone showing the new design;

FIG. 9 is a Front Elevational view thereof;

FIG. 10 is a Rear Elevational view thereof;

FIG. 11 is a Left Side Elevational view thereof;

FIG. 12 is a Right Side Elevational view thereof;

FIG. 13 is a Top view thereof; and,

FIG. 14 is a Bottom view thereof.

The broken lines to a part of the headset for telephone forms no part of the claimed design.

1 Claim, 14 Drawing Sheets
